(57) **CLAIM**

The ornamental design for equipment for control of electric power, as shown and described.

DESCRIPTION

FIG. 1 is a top perspective view of equipment for control of electric power showing our new design;

FIG. 2 is a front view thereof;

FIG. 3 is a right side view thereof;

FIG. 4 is a left side view thereof;

FIG. 5 is a back view thereof;

FIG. 6 is a top plan view thereof;

FIG. 7 is a bottom plan view thereof;

FIG. 8 is a top front perspective view of an alternative embodiment of equipment for control of electric power showing our new design;

FIG. 9 is a front view thereof;

FIG. 10 is a right side view thereof;

FIG. 11 is a left side view thereof;

FIG. 12 is a back view thereof;

FIG. 13 is a top plan view thereof; and,

FIG. 14 is a bottom plan view thereof.

The broken lines shown in the figures are for the purpose of illustrating portions of the equipment for control of electric power and form no part of the claimed design.

1 Claim, 14 Drawing Sheets
